(57) **CLAIM**

The ornamental design for a window mountable heat pump, as shown and described.

DESCRIPTION

FIG. 1 is a top view of a window mountable heat pump showing my new design;

FIG. 2 is a perspective view thereof;

FIG. 3 is a front view thereof;

FIG. 4 is a rear view thereof; and,

FIG. 5 is a side view thereof.

The broken lines in the figures are for the purpose of illustrating portions of the window mountable heat pump that form no part of the claimed design.

1 Claim, 5 Drawing Sheets
